Attorney

UNITED STATES PATENT OFFICE.

EDWARD SAADI, OF BROOKLYN, NEW YORK.

PENCIL.

Application filed March 26, 1924. Serial No. 702,034.

To all whom it may concern:

Be it known that I, EDWARD SAADI, citizen of the United States, residing at Brooklyn, in the county of Kings and State of New York, have invented certain new and useful Improvements in a Pencil, of which the following is a specification.

This invention relates to new and useful improvements in pencils and has for its 10 principal object to provide a device whereby the lead carrying barrel is normally supported in a retracted position, means being associated with the pencil for automatically causing the extrusion of the forward end of 15 the barrel whereby the lead is moved to an operative position when the pencil casing is grasped by the person using the same.

A still further object of the invention is to provide a pencil of the above mentioned 20 character, wherein means is associated with the barrel and the forward end of the casing for feeding the lead outwardly from the barrel as the same is used.

A still further object of the invention is 25 to provide a pencil of the above mentioned character, wherein means is provided for returning the barrel to its normal retracted position when the pencil casing is released from the hand of the person using the same.

A still further object of the invention is 30 to provide a pencil of the above mentioned character, which is simple in construction, inexpensive, strong and durable and furthermore adapted for the purposes for which it is designated.

Other objects and advantages of this invention will become apparent during the course of the following description.

In the accompanying drawings forming a 40 part of this specification and in which like numerals designate like parts throughout the same,

Figure 1 is a sectional view through the lower portion of the pencil with parts shown 45 in side elevation,

Figure 2 is a fragmentary sectional view of the lower portion of the pencil with parts shown in side elevation, the barrel being shown in an extended position,

Figure 3 is an enlarged fragmentary sectional view of the pencil lead feeding means,

Figure 4 is a transverse section taken approximately on line 4-4 of Figure 1,

Figure 5 is a transverse section taken approximately on line 5-5 of Figure 1,

Figure 6 is a transverse section taken approximately on line 6-6 of Figure 1,

Figure 7 is a fragmentary detail perspective view of the barrel head, and

Figure 8 is a transverse section taken approximately on line 8-8 of Figure 3.

In the drawings wherein for the purpose of illustration is shown the preferred embodiment of my invention, the numeral 1 designates the casing of my pencil and the same is substantially cylindrical in cross section as is clearly shown in the drawings. The forward end of the casing 1 is open and is internally threaded as is shown at 2 in the drawings. The casing 1 is further provided with a partition 3 whereby an upper compartment 4 and a lower compartment 5 are respectively formed. Adapted to be placed in the compartment 4 are the extra leads 6. For the purpose of preventing the accidental displacement of the leads from within the compartment 4 I provide the upper end of the casing 1 with a removable closure 7.

Adapted to be supported in the lower end 80 of the casing 1 and threaded into engagement with the threaded portion 2 thereof is the section 8. The lower or opposite end of the section 8 is provided with an annular groove 9 and the purpose of this arrangement will be presently described. Cooperating with the stationary section 8 is the rotatable section 10 and the same has its upper end provided with an inwardly extending annular bead 11 for cooperation with the 85 annular groove 9 formed in the lower end of the section 8 in the manners clearly shown in Figures 1 and 2 of the drawings. The lower end of the rotatable section is tapered and carries at the extreme outer end thereof 90 the tip 12 in which is formed the opening 13.

Carried by the inner walls of the stationary section 8 intermediate its ends is the annular flange 14. Also formed integrally on the inner wall of the rotatable section 10 100 adjacent the lower edge of the stationary section 8 is the spirally arranged annular flange or ring member 15 the same being split so that the respective ends thereof will be spaced apart in the manner shown at 16 in 105 Figure 8 of the drawings. The purpose of this construction will also be hereinafter more fully described.

Slidably supported in the lower end of the casing 1, and through the stationary and 110

rotatable sections 8 and 10 respectively is the barrel 17 in which is adapted to be supported a pencil lead in the manner clearly shown in the drawings. The barrel 17 is 5 provided with the longitudinally extending slot 18. The upper end of the barrel 17 supports thereon the head section 19 and the same is provided with the inclined face 20. The head section 19 is provided for the 10 purposes of forcing the barrel 17 outwardly from the lower end of the rotatable section 10 when the pencil is in use. Normally the barrel 17 is held in a retracted position so that the lower end thereof will be normally 15 disposed within the tip 12 of the rotatable section 10 and for the purpose of holding the same in this position, I provide the barrel 17 with the collar 21, the same being secured thereto in any suitable manner and 20 supported on the barrel so as to be disposed within the upper portion of the stationary section 8. A suitable coil spring such as is shown at 22 encircles the barrel 17 and is disposed between the collar 21 and the annular flange 14 and has its ends secured thereto in any suitable manner. The spring 22 will normally force the collar 21 and the barrel 17 carried thereby upwardly in the manner as shown in Figure 1 of the drawings 25 whereby the lower end of the barrel will be held in a retracted position.

For the purpose of extruding the lower end of the barrel 17 outwardly from the lower end of the pencil when it is desired to 30 use the same, I provide a casing 1 with a curved spring 23 which is secured at one end as shown at 24 and the intermediate portion or the bowed portion of the spring carries thereon the plunger 25. The plunger 25 extends through a suitable opening 26 provided in the side of the casing in the lower compartment 5 and the inner end of the plunger is provided with an inclined face 27 for cooperation with the inclined 35 face 20 of the head section 19. When the person using the pencil desires to project the barrel and the lead carried thereby, a spring 23 is pushed inwardly against the casing so that the plunger 25 will have its 40 inclined face 27 riding on the inclined face 20 of the section 19 and thus cause the downward sliding movement of the barrel 17 through the flange 14 and spiral ring 15 in the stationary and rotatable sections respectively so that the lower end of the 45 barrel will project beyond the lower end of the rotatable section of the pencil in the manner clearly shown in Figure 2 of the drawings. This operation causes a downward 50 movement of the collar 21 so as to result in the compression of the spring 22. When the person releases the spring 23, the plunger 25 will simultaneously return to its normal position and the coil spring 22 will 55 cause the barrel and head section carried

thereby to be returned to their normal positions whereby the lower end of the barrel will be disposed within the tip 12.

For the purpose of feeding the lead 6 which is supported in the lower end of the barrel 17 outwardly therefrom so that a sufficient amount of lead may extend from the barrel for use for an indefinite period, a follower 28 is disposed in the barrel 17 on top of the lead in the manner shown in Figures 1 and 3 of the drawings. The follower 28 is provided with laterally extending teeth 29 which are arranged in spaced relation and the teeth extend through the slot 18 in such a manner as to permit the spiral ring 15 carried by the rotatable section 10 to engage the same. When the rotatable shell 10 is actuated, the turning of the same will also cause the operation of the spiral ring 15 and the spiral ring 15 is in engagement with the teeth 29, the same will cause the follower to force the lead outwardly through the lower end of the barrel thus permitting all of the lead to be used and eliminating any loss thereof. The provision of the groove 9 and the coacting bead 11 permits the adjustment or rotation of the section 10 on the section 8 whereby the lead 6 may be fed outwardly from the barrel.

It will thus be seen from the foregoing description, that a lead pencil has been provided which is very simple in construction, inexpensive, strong and durable, the parts being so arranged as to permit the same to be easily and readily disassembled whenever necessary, and the barrel carrying the lead will normally be held in a retracted position, thus preventing the lead which extends beyond the barrel from being broken off accidentally when the pencil is not in use. The simplicity in which my invention operates enables the same to be at all times easily and quickly actuated when it is desired to use the pencil and when the pencil is not in use the parts will automatically return to their normal inoperative positions.

While I have shown the preferred embodiment of my invention, it is to be understood that various changes in the size, shape and arrangement of parts may be resorted to without departing from the spirit of the invention and the scope of the appended claims.

Having thus described the invention, what I claim is:

1. A pencil comprising a casing having an opening in the wall thereof, the lower end thereof tapering and provided with an opening, a barrel slidably mounted in the lower end of said casing, said barrel adapted to hold a pencil lead, a spring for normally holding the lower end of the barrel within the lower end of the casing, and means ex-

tending through the opening in the wall of the casing for engaging and moving said barrel downwardly to extrude the lower end of the barrel beyond the lower end of the 5 casing, and means for feeding said lead outwardly from the barrel.

2. A pencil comprising a casing having an opening in the wall thereof, the lower end of the casing tapering and provided with an 10 opening, a lead receiving barrel slidably mounted in the lower end of said casing, and adapted to operate through the opening in the lower end of the casing, means for normally holding the lower end of the barrel 15 inwardly of the lower end of the casing, a head section on the upper end of said barrel, said head section having an inclined face, a plunger extending through the opening in the wall of said casing adapted to 20 engage the inclined face of said head section and move the same and the barrel downwardly in the casing to project the lower end of the barrel beyond the lower end of the casing.

25 3. A pencil comprising a casing having an opening in the wall thereof, the lower end of the casing tapering and provided with an opening, a lead receiving barrel slidably mounted in the lower end of said casing, and 30 adapted to operate through the opening in the lower end of the casing, means for normally holding the lower end of the barrel inwardly of the lower end of the casing, a head section on the upper end of said barrel, 35 said head section having an inclined face, a plunger extending through the opening in the wall of said casing adapted to engage the inclined face of said head section and move the same and the barrel downwardly 40 in the casing to project the lower end of the barrel beyond the lower end of the casing, and means associated with said plunger for normally holding the same in an inoperative position.

45 4. A pencil comprising a casing open at its lower end, a stationary section supported in the lower end of the casing, said stationary casing being tubular, a rotatable section mounted on the lower end of the stationary 50 section and being substantially tubular in cross section, the lower end of said rotatable section being tapered and provided with an opening, a lead receiving barrel slidably supported in the lower end of said casing 55 and extending through said sections, means for normally holding the lower end of the barrel within the lower end of the rotatable section, means for moving said barrel downwardly through said sections so as to project the lower end of the barrel beyond the lower 60 end of the rotatable section, and means associated with said rotatable section and said barrel for feeding the lead in the barrel outwardly therefrom.

65 5. A pencil comprising a casing open at

its lower end, a stationary section supported in the lower end of the casing, said stationary casing being tubular, a rotatable section mounted on the lower end of the stationary section and being substantially tubular in 70 cross section, the lower end of said rotatable section being tapered and provided with an opening, a lead receiving barrel slidably supported in the lower end of said casing and extending through said sections, means 75 for normally holding the lower end of the barrel within the lower end of the rotatable section, means for moving said barrel downwardly through said sections so as to project the lower end of the barrel beyond the lower 80 end of the rotatable section, and means associated with said rotatable section and said barrel for feeding the lead in the barrel outwardly therefrom, said means comprising a follower supported in the barrel on top of 85 the lead therein, teeth formed on the follower and extending outwardly from the barrel through a slot provided therein and a spiral ring carried by the rotatable section and adapted to engage said teeth to 90 move said follower downwardly upon the rotation of the rotatable section.

6. A pencil comprising a casing having an opening provided in the wall thereof, the lower end of said casing being open, a tubular stationary section supported in the lower end of said casing, an additional section mounted on the lower end of said stationary section and having its lower end tapering and provided with an opening, an annular 100 flange mounted on the inner wall of the stationary section, a barrel adapted for slidable movement in the lower end of said casing and through said sections, a collar carried by the said barrel and disposed in the stationary section above said flange, a coil spring encircling said barrel and disposed between said flange and said collar for normally holding the barrel in its retracted position, 105 and means associated with the upper end of the barrel for forcing the same downwardly through said sections so that the lower end of the barrel will extend beyond the lower end of the tapered section, said means comprising an enlarged head carried by the upper end of the barrel and provided with an 110 inclined face, a curved spring secured at one end to the outer face of the casing, a plunger carried by the bowed portion of said spring and extending through the wall in the casing, the inner portion of said plunger having an inclined face for engagement with the inclined face of the head section, said plunger adapted to move the head section and the barrel carried thereby downwardly 115 upon the inward movement of the curved spring and the plunger.

In testimony whereof I affix my signature.

EDWARD SAADI.
